UNITED STATES PATENT OFFICE.

FREDERIC J. HOFSCHEIDER, OF ROCHESTER, NEW YORK.

HYPODERMIC SYRINGE.

Application filed March 13, 1926. Serial No. 94,579.

My invention relates to a hypodermic syringe, and more particularly to the general type disclosed in my co-pending application Serial No. 67,144, filed November 5, 1925, in which a tapered needle carrier is held frictionally in a tapered portion of the barrel opening, the piston being removable from the barrel to permit insertion of a needle carrier through the barrel.

10 The object of the invention is to provide a simplified, economical, and practicable means for loosening the needle carrier in the barrel when desirable to remove the same.

In a more particular aspect, the invention 15 has for its purpose to employ the piston to loosen the needle carrier from the barrel, this result being preferably accomplished by the provision of interlocking means between the piston and needle carrier such that when 20 the piston is turned, the needle carrier is likewise turned within the tapered portion of the barrel and thereby loosened.

To these ends, the invention consists in the construction and arrangement of parts 25 that will appear clearly from the following description when read in conjunction with the accompanying drawing, the novel features being pointed out in the claims following the description.

30 In the drawing:

Figure 1 is a side elevation, partly in section, of a hypodermic syringe incorporating a preferred embodiment of the invention, the piston appearing in normal position at 35 the end of its stroke;

Figure 2 is an enlarged sectional view, partially broken away, and showing the piston in interlocking engagement with the needle carrier, and

40 Figure 3 is a perspective view of the inner end of the needle carrier.

Referring more particularly to the drawing in which like reference numerals refer to corresponding parts throughout the several views, 1 designates the barrel, 2 is the tapered needle carrier held frictionally in a correspondingly tapered portion at the outer end of the barrel opening, and 3 is the piston, all arranged and functioning in the general manner set forth in my aforesaid application.

The needle carrier is positioned within the barrel by inserting it, needle downwardly, into the inner end, after the piston has first 55 been removed. The needle carrier is then permitted to fall to the outer end of the

barrel, and the piston inserted and moved toward the outer end of the barrel to give a slight blow to the needle carrier with sufficient force so that the latter is held tightly 60 in place by its frictional engagement with the tapered part of the opening. The syringe is then ready for use, after which, when desired to remove the needle carrier, it must first be loosened, and this I accomplish through the instrumentality of the piston, which is turned while in interlocking engagement with the needle carrier.

Various ways of effecting this result are possible, and to illustrate the idea, I have 70 shown the needle carrier and piston provided on their adjacent ends with abutments or lugs 4 and 5, which are undercut at 6 and 7 respectively. By moving the piston outwardly and turning it until its abutment 75 4 engages the recess adjacent to abutment 5 on the needle carrier, the said abutments interlock one with the other as shown in Figure 2. Then when the piston is turned, and simultaneously pulled, the needle carrier 80 is turned with it, and at the same time moved inwardly, due to the cooperation of said undercut portions 6 and 7, a very slight turning and pulling movement of the piston being sufficient to loosen the needle carrier 85 from the barrel. The piston is then removed and upon inverting the barrel, the needle carrier will fall therefrom. With this arrangement, it is practicable to use a fresh, sterile needle each time the syringe is used, 90 very little time being required for positioning and removing the needle carrier. No additional tool is necessary, and the piston, which is always with the syringe, can be instantly manipulated to either secure the 95 needle carrier in place frictionally, or effect its removal from the barrel.

This invention also lends itself to a safer and more sterile operation where a needle is used more than once on the same patient. 100 Ordinarily, after a needle is used, when the piston is withdrawn to prepare for a second filling of the needle, any germs or poisonous matter in the needle is sucked back into the barrel of the syringe and becomes mixed 105 with the fresh solution, greatly endangering the patient. With my invention, this can be prevented, by slightly loosening the needle carrier as already described, before withdrawing the piston. This will admit air to 110 the barrel and eliminate the chance of sticking the contents of the needle back into the

barrel. Before inserting the new solution, the needle carrier is tightened again by moving the piston outwardly and tapping the needle carrier with it, which at the same time forces out from the needle any foreign matter contained therein, and prevents contamination of the fresh solution. And it is noteworthy that the needle can thus be controlled by a simple and slight manipulation 10 of the piston, and without ever touching the needle or needle carrier.

While the invention has been described with reference to a certain particular embodiment, it is not limited to the details 15 herein disclosed, and this application is intended to cover such modifications or departures as may come within the intent of my invention or the scope of the following claims.

20 I claim:

1. In a hypodermic syringe, the combination with a barrel, of a needle carrier held therein, a piston movable in the barrel, and means carried by the piston for cooperation 25 with the needle carrier to effect removal of the latter from the barrel, said cooperation taking place while said piston is within the barrel.

2. In a hypodermic syringe, the combination with a barrel having an opening with 30 an inwardly tapering portion at its outer

end, of a removable tapered needle carrier held frictionally in said tapered portion of the opening, a removable piston in the barrel, and means carried by the piston engageable with the needle carrier to remove the latter from the barrel.

3. In a hypodermic syringe, the combination with a barrel having an opening with an inwardly tapering portion at its outer 40 end, of a removable tapered needle carrier held frictionally in said tapered portion of the opening, a removable piston in the barrel, and cooperating means on the needle carrier and piston whereby turning of the 45 piston effects turning of the needle carrier to loosen the latter for removal from the barrel.

4. In a hypodermic syringe, the combination with a barrel having an opening with 50 an inwardly tapering portion at its outer end, of a removable tapered needle carrier held frictionally in said tapered portion of the opening, a removable piston in the barrel, and cooperating interlocking abutments 55 on the piston and needle carrier whereby turning of the piston effects turning of the needle carrier to loosen the latter for removal from the barrel.

In witness whereof, I have hereunto signed my name.

FREDERIC J. HOF SCHNEIDER.
